UNITED STATES PATENT OFFICE.

AUGUST FRIEDERICI, OF COLOGNE-MULHEIM, GERMANY, ASSIGNOR TO MAX FRIEDERICI, OF STEUBENVILLE, OHIO.

ELECTRICALLY-DRIVEN FORGING PRESS.

Application filed May 13, 1926, Serial No. 108,807, and in Germany July 14, 1925.

This invention relates to forging presses and more particularly to electrically operated forging presses, and has for one of its objects the provision of a press of this class with novel adjusting means whereby the stroke of the forging ram may be adjusted at will and during the operation of the press.

Another object is to provide a novel combination of elements for preventing the over-charging of the press.

Another object is to provide a press having the novel design, construction and combination of parts hereinafter described.

15 In the drawings:

Fig. 1 illustrates the side view of the forging press, Fig. 2 the front view, Fig. 3 a horizontal section through the frame of the press, and Fig. 4 a section through the cylinder for the prevention of fracture.

Referring more particularly to the drawings, the letter A designates the frame of the machine as a whole, which is provided at its forward side with a throat 2. An anvil 3 is mounted in the frame A at the base of the throat, and a forging ram 4 is slidably mounted in bearings 5 on the forward face of the frame above the throat and is adapted to be reciprocated to forge workpieces 30 mounted on the anvil.

The upper part or shank of the ram 4 is slotted, as at 4^a, to receive the forward end of a rocking lever 6, which lever is fulcrumed on a fulcrum shaft 7. The shaft 7 is mounted in a vertically disposed screw-spindle 8 journaled in the frame A and adapted to be adjusted vertically to raise or lower the position of the fulcrum shaft 7. A nut 9 is mounted on the spindle 8 and journaled in the frame A, and has an integral worm-wheel 10 formed thereon, which is meshed with a worm 12 on the armature shaft of a motor 13, to provide for power adjustment of the spindle. A pair of bearing and guide blocks 14 are mounted on the shaft 7 and within guide slots 15 in the frame A, so as to guide the shaft 7 when the spindle 8 and shaft 7 are moved vertically.

The rocking lever 6 is fulcrumed on the shaft 7 at a point toward its forward end from its vertical center line so as to provide a forward short arm 7^a and a long rear arm 7^b.

The forward end of the lever 6 is con-

nected by a link mechanism 16 and 17 to the ram 4 so as to reciprocate the ram.

The rear end of the lever 6 is forked and pivotally connected to trunnions 18 secured in the wall of a pressure cylinder 19. The cylinder 19 has a piston 20 therein connected to a piston rod 21 which projects below the cylinder 19 and is connected to the crank portion 22 of a crank shaft 23 journaled in bearings 23^a on a bracket 24 on the frame A.

A liquid supply cylinder 25 is mounted on top of the cylinder 19 and is adapted to be filled with liquid to be drawn into the cylinder 19. An inlet valve port 26 forms a communicating passage between the cylinders 25 and 19, which is normally closed by a valve 27 connected to a valve rod 28 projecting upwardly through the cylinder 25. A valve spring 29 is mounted around the portion of the valve rod 28 above the cylinder 25 and is held under tension by nuts 30.

An escape or outlet valve port 31 is formed between the cylinders 25 and 19 and is normally closed by a spring pressed valve 32 adapted to open automatically when the pressure of the fluid in the cylinder 19 exceeds a predetermined maximum. The valve 32 is provided with a valve rod 33 which extends upwardly through the cylinder 25.

A valve spring 34 is mounted around the rod 33 and is normally held under compression by a sleeve 35 slidably mounted on the rod 33 and threaded in a nut 36. The nut 36 is held against rotation by a pair of guide rods 37. A lock-nut 38 is threaded on the rod 33 to limit the movement of the sleeve 35.

In operation, when the piston 20 is moved downwardly, fluid from the cylinder 25 will be drawn into the cylinder 19 through the valve port 26, and when the piston is moved upwardly on the working stroke, the fluid previously drawn into the cylinder 19 is compressed, and if the compression exceeds a predetermined maximum, the valve 32 will automatically open to allow the escape of at least a portion of the liquid from the cylinder 19 into the cylinder 25.

The downward stroke of the rear end of the lever 6 is limited by a cam 39 mounted on a shaft 40. The shaft 40 carries a pinion 41 in mesh with a gear 42 on a stub shaft 43 which is meshed with a rack segment 44. The rack segment 44 is formed integral with a rocking lever 45 fulcrumed on a stub shaft

46, and has its forward end connected by a connecting link 47 with the shaft 7, so that as the shaft 7 is adjusted vertically the rack segment 44 will be operated to cause the cam stop 39 to be moved through the gears 41 and 42.

The crank shaft 23 is provided with a gear 48 which is meshed with a pinion 49 on a shaft 50. The shaft 50 also carries 10 a gear 51 which is in mesh with a pinion 52 on a shaft 53 coupled to the armature shaft 54 of a variable speed motor 55.

An indicator finger 56 is secured to one of the bearing blocks 14 and is adapted to 15 be moved along a fixed scale 57 on the frame A. The scale 57 is so arranged that the finger 56 indicates a dimension corresponding to the distance between the upper face 20 of the anvil and the lower face of the ram when the ram is in its lowermost position, thus it is possible to adjust the fulcrum 25 of the lever 6 so as to forge or press work-pieces at the desired thickness within the limits of the scale without gaging the work-pieces.

In operation, the motor 55 drives the crank shaft 23 through the gears 52, 51, 49 and 48, and the crank shaft operates or rocks the lever 6 through the piston rod 21, piston 20 and cylinder 19. The lever 6 rocks about 30 the shaft 7, and the shorter end 7^a operates the ram 4, while its longer end 7^b serves as a receiving lever to receive the power from the crank shaft 23 and transmit it to the short or ram operating end.

The fulcrum shaft 7 of the lever 6 is 35 adapted to be adjusted vertically by means of a nut 9, worm-wheel and worm 10 and 12, and motor 13 so as to vary the amount of movement of the lever 6 and consequently 40 the amount of movement of the ram 4. An indicator 56 and scale 57 cooperate to indicate the distance between the ram 4 and anvil 3 at the various points of adjustment 45 of the shaft 7.

The cylinders 19 and 25 and their co-operating mechanism form an over-pressure safety or relief connection to prevent the apparatus exceeding a predetermined maximum power.

50 While I have shown and described one

specific embodiment of my invention, it will be understood that I do not wish to be limited thereto since various modifications may be made without departing from the scope 55 of my invention as defined in the appended claims.

I claim:

1. In a forging press having an anvil and a reciprocatory ram, a rocking lever for reciprocating said ram, a vertically adjustable fulcrum for said rocking lever, a crank shaft, overpressure relief means operatively connecting said crank shaft and said lever, and adjustable means for limiting the downward movement of the end of said lever opposite from said ram, said means including a cam shaft, a cam on said shaft adapted to engage and limit the downward movement of said lever, and means operable by the vertical movement of said fulcrum for rotating said cam shaft to vary the position of said cam and thereby vary the downward movement of said lever.

2. A forging press comprising a housing, 75 an anvil on said housing, a reciprocatory ram, a rocking lever for reciprocating said ram, a fulcrum shaft for said lever, said fulcrum shaft being vertically movable relative to said housing, a vertical screw spindle 80 journaled in said housing and supporting said fulcrum shaft, a nut having a threaded engagement with said spindle and journaled in said housing, power means for operating said nut to cause a vertical movement of said spindle and said fulcrum shaft, and adjustable means for limiting the downward movement of the rear end of said lever, said means including a cam shaft, a cam on said shaft adapted to engage and limit the downward movement of said lever, a pinion on said cam shaft, and means including a rocking lever having a rock segment thereon in mesh with said pinion and operable by the vertical movement of said fulcrum shaft for 95 rotating said cam shaft to vary the position of said cam and thereby vary the downward movement of said lever.

In testimony whereof I have hereunto set my hand.

AUGUST FRIEDERICI.
